DISPLAY CARTONS

Warren Nevins, Monmouth Junction, N.J.

Application August 28, 1957, Serial No. 680,852

5 Claims. (Cl. 229—28)

This invention relates to improved display cartons and particularly, but not necessarily exclusively, to improved cartons for fragile articles, such as eggs. The cartons herein both provide protection of the contents and permit inspection of the contents thereof without opening the carton.

Many research studies have shown that consumers prefer to buy food products in packages which display the contents thereof. When given a choice, consumers prefer to purchase eggs, for example, packed in transparent cartons. The reason for the preference is that transparent cartons enable the consumer to examine the eggs for size, condition, cleanliness, etc.

Previously, in the case of eggs, two avenues of approach have been followed to provide a carton which permits the inspection of the contents thereof. One approach is to cut windows in a conventional egg box. While this type of carton is inexpensive, it has the disadvantages that only a small portion of each egg is displayed and that heavier materials are necessary to strengthen the carton. Another approach is to provide an egg box of transparent plastic. In this case, the entire egg is displayed, but the carton is not sturdy enough to adequately protect the eggs and is relatively expensive.

An object of this invention is to provide an improved display carton.

A further object is to provide improved egg cartons which adequately protects the eggs therein, while permitting inspection of the contents without opening the carton.

In general, a display carton of the invention comprises two upper and two lower walls arranged in a substantially unitary X-shaped configuration, each pair of an upper and a lower wall having opposed openings therein adapted to hold articles therebetween in compression, and means maintaining a compressive force between each pair of an upper and a lower wall when an article resides therebetween.

The display carton of the invention is preferably made of a single piece cardboard or other blank material and comprises generally a lower rectangular base, two lower inclined walls each attached to one of the longitudinal edges of said lower base and converging upwardly with respect to each other, an upper rectangular base, two upper inclined walls each attached to one of the longitudinal edges of said upper base and converging downwardly with respect to each other, means holding together the upper edges of said two lower walls and the lower edges of said two upper walls to form a substantially unitary X-shaped structure. Each set of said upper and lower walls having opposed openings therein adapted to hold articles therebetween in compression; and said upper and lower bases having openings therein permitting inspection of articles held between said walls.

An article to be displayed, such as an egg, is placed in the opposed openings between an upper wall and a lower wall and are held therebetween by positive compressive force acting on the article. Unlike previous cartons which merely provide a cradle for each article, the cartons

2

herein hold each article in compression preventing movement of the articles. After the carton is filled with the desired articles, the carton may be wrapped in cellophane or other transparent sheet material. The wrapped assembly provides a complete display of the contents and still maintains adequate protection for the contents.

Further improvements are provided to display cartons herein by providing (1) transverse members in the bases, (2) transverse partitions between the upper walls, and/or the lower walls, which aid in maintaining a uniform compressive force on each article held in the carton, and (3) auxiliary flaps attached to or integral with the lower base which contact the articles preventing rotation thereof.

The foregoing objects and other advantages are more fully explained in the following detailed description when read in conjunction with the drawings in which:

Figure 1 is a partially sectional front elevational view of a carton of the invention viewed along lines 1—1 of 20 Figure 3,

Figure 2 is a side elevational view of the carton of Figure 1,

Figure 3 is a plan view of the carton of Figure 1, and Figure 4 is a plan view of the punched blank used to

25 prepare the carton of Figure 1.

Similar reference characters are used for similar structures throughout the drawing.

Referring to Figures 1 to 4, the display carton herein may be prepared from a single sheet of punched or die 30 cut blank material 21 such as cardboard, as shown in Figure 4. The cartons herein may also be prepared from several pieces. The punched sheet 21 is folded to form a closed X-shaped configuration.

More specifically, the punched blank material is folded 35 to form a lower rectangular base 23; a lower left inclined wall 25 integral with the left longitudinal edge 23a of said lower base 23; a lower right inclined wall 27 integral with the right longitudinal edge 23b of said lower base 23, said lower left and lower right walls 25 and 27 converging 40 upwardly with respect to each other; an upper right wall 31 integral with the upper longitudinal edge 27a of said lower right wall 27; an upper rectangular base 33 integral with the upper longitudinal edge 31a of said upper right wall 31 and substantially parallel to said lower base 23; an upper left wall integral with the left longitudinal edge 33a of said upper base 33, said upper left and right walls 29 and 31 converging downwardly with respect to one another to form an X-shaped structure.

Means are provided for holding the lower longitudinal edges of the upper walls 29 and 31 and the upper longitudinal walls of the lower walls 25 and 27 together. Such holding means may be flaps and staples placed at 50 convenient intervals along the length of the edges 25a and 27a. A preferred holding means comprises a set of flaps punched in the upper and lower bases 23 and 33 which fold to engage the walls. As shown in the drawings, upper end flaps 41a to 41d punched in the upper base 33 are folded downwardly to a position at about right angles to the upper base 33, engaging the upper left and upper right walls 29 and 31 in recesses 45a to 45d thereof respectively and also engaging the lower left and lower right walls 25 and 27 in recesses 39a, 39g, 39h and 39f therein respectively. Upper center flaps 43a to 43d punched in the upper base 33 are folded downwardly to a position at about right angles to the upper base 33 engaging the upper right and upper left walls 29 and 31 in slots 47a to 47b therein respectively. Lower end flaps 55 35a and 35b and lower center flaps 37a to 37d punched in the lower base 23 are folded upwardly to a position at about right angles to the lower base 23 engaging the lower left and lower right walls 25 and 27 in recesses 39a to 39f therein and bear against upper left and upper

right walls 29 and 31. The upper and lower flaps engaged with the upper and lower walls provide rigidity and unity to the structure.

The carton is symmetrical about a vertical axis 99 as shown in Figure 1. The description which follows will be with respect to the section to the right of the axis 99. It will be understood that a corresponding left section is also provided which is a mirror image of the right section. Further, throughout this specification one may reverse the positions of right and left to produce a mirror image carton of the carton of the example.

Opposed portions of the upper and lower right walls have opposed openings therein, each pair adapted to hold a fragile article 53a, such as an egg, therebetween in compression. As shown in the drawings, there are six pairs of openings for holding six articles on each side of the carton. The carton may be designed to hold more or less than this number. The lower right wall 27 has lower right openings 49a to 49f. The upper right wall 31 has upper right openings 51a to 51f opposite the lower right openings 49a to 49f respectively.

A typical article 53a is pressed into a pair of opposed openings and is held there by compression from the walls 27 and 31. The carton herein, while being a rigid, unitary structure is nevertheless resilient because the novel design herein is aided by the nature of the material of which it is made. Fragile articles may thereby be slipped in or pulled out from the side of the carton with ease, and still be held firmly in place when the article resides in the carton.

To further strengthen the carton without affecting the resiliency, it may be desirable to provide transverse members in the upper and lower bases. To this end, the lower base 23 is provided with transverse members 57a, 57b and 57c integral therewith. Upper base 33 is provided with transverse members 59a, 59b and 59c integral therewith.

Where the filled or partially filled carton is subject to vibration, an unsymmetrical article frequently rotates in its position in the carton. To reduce this tendency, it may be desirable to provide an auxiliary flap which applies additional pressure to the article to prevent rotation. The auxiliary flap may be made integral with one of the sections of the carton, such as the lower base 23. As shown in the drawings, an auxiliary flap 61a comprises a folded strip of cardboard stapled at convenient intervals 63 to the lower base 23, extending upwardly at about right angles to the lower base 23, and bearing against lower center flaps 37a to 37d. When an article is pressed into the carton, the article presses against the auxiliary flap 61a. The auxiliary flap 61a is held in pressure contact with the article and the lower center flaps due to the resiliency of the auxiliary flap material.

After assembly, the display carton herein may be loaded from the side either mechanically or by hand. Following loading, the carton is preferably wrapped in a transparent web material such as cellophane and sealed. Such wrapping, while not necessary, nevertheless aids in maintaining compression upon the articles in the carton.

The display cartons herein have at least the following advantages:

(1) They are low in cost because the nature of their rigid construction permits the use of lighter punched or die cut blank material than conventional cartons.

(2) They permit easy loading and unloading from the side without the need of opening and closing a cover. Further, the loading operation is easily and simply mechanized.

(3) They permit complete inspection of their contents without opening or unwrapping the carton.

(4) They hold each article in compression preventing shaking and rattling in the carton thereby avoiding damage due to vibration, and

(5) They may be stacked one upon the other with-

out damage to the contents therein, since the articles are cushioned on all sides preventing damage due to pressure on top and sides. Further, the articles themselves contribute in part to the strength of the loaded carton.

What is claimed is:

1. A display carton comprising two upper and two lower longitudinal walls arranged in a substantially unitary X shaped configuration, each pair of an upper and a lower wall having opposed openings therein adapted to hold articles therebetween in compression, and transverse walls locked into said two upper and two lower longitudinal walls between adjacent opposed openings for maintaining a compressive force between each pair of an upper and a lower wall when an article resides therebetween.

2. The carton of claim 1 including a wrapping of transparent material around the entire carton.

3. A display carton comprising a lower rectangular base, two lower inclined longitudinal walls each attached to one of the longitudinal edges of said lower base and converging upwardly with respect to each other, an upper rectangular base, two upper inclined longitudinal walls each attached to one of the longitudinal edges of said upper base and converging downwardly with respect to each other, means holding together said two lower walls and said two upper walls to form a substantially unitary structure; each set of said upper and said lower walls having opposed openings therein adapted to hold articles therebetween in compression; and transverse walls locked into said two upper and two lower longitudinal walls between adjacent opposed openings for maintaining a compressive force between each pair of an upper and a lower wall when an article resides therebetween.

4. An egg carton comprising a lower rectangular base, a right lower inclined wall integral with the right longitudinal edge of said lower base, a left lower inclined wall integral with the left longitudinal edge of said lower base, said right and left walls converging upwardly in respect to one another, a right upper inclined wall integral with the upper longitudinal edge of said right lower inclined wall, an upper rectangular base integral with the upper longitudinal edge of said right upper inclined wall, a left upper inclined wall integral with the left longitudinal edge of said upper base, said right and left upper walls converging downwardly with respect to each other, means maintaining said upper longitudinal edge of said lower left inclined wall with the lower longitudinal edge of said upper left inclined wall, the lower base having lower flaps punched therein and folded upwardly to lock into said right and left lower wall sections, said upper base having flaps punched therein and folded downwardly to lock into said right and left upper wall sections, opposed portions of upper and lower right walls having openings therein adapted to hold eggs therebetween in compression, opposed portions of said upper and lower left walls having openings therein adapted to hold eggs therebetween in compression, a first auxiliary flap attached to said lower base and extending upwardly therefrom to provide a pressure contact to eggs held between said upper and lower right wall sections and a second auxiliary flap attached to said lower base and extending upwardly therefrom to provide a pressure contact to eggs held between said upper and lower left wall sections.

5. An egg carton characterized by permitting eggs contained therein to be substantially completely viewable without unloading comprising two upper and two lower longitudinal walls arranged in a substantially X shaped configuration each pair of an upper and lower wall having opposed openings therein adapted to hold eggs therebetween in compression with the long axis of each egg normally in a substantially vertical position; and substantially vertical transverse walls between adjacent opposed openings locked into each pair of upper walls

and each pair of lower walls for maintaining a compressive force on eggs held therebetween.
